UNITED STATES PATENT OFFICE

LOUIS LICHTMAN, OF NEW YORK, N. Y., ASSIGNOR TO CHROMEPLATE, INC., OF NEW YORK, N. Y., A CORPORATION OF NEW JERSEY

HANGER FOR ARTICLES TO BE PLATED

Application filed November 27, 1928. Serial No. 322,222.

This invention is an improvement in hangers for articles to be plated, and more particularly in a hanger for chromium plating, enabling the articles to be supported in the most favorable position for receiving the deposit.

In electro-plating, the article is the cathode, and to obtain a maximum of efficiency, a good electrical connection must be maintained between the article and the hanger, with which the negative lead of the circuit is connected.

In certain ware, such as lengths of inter-linked units, as for instance, chains, and like flexible articles, a firm grip of the article, with good electrical connection, is difficult to obtain, and it is desirable in supporting ware of this character, that the contact be at a plurality of points, as widely spaced as possible, and that the length be held on the stretch to provide close contact between the units.

One of the primary objects of the present invention is the provision of a type of hanger, especially adapted for supporting this class of ware, wherein the supporting elements of the hanger are so arranged as to hold the ware on the stretch, and resiliently, so that efficient contact is obtained throughout the length of the article.

Another object is the provision of means in connection with the supports for holding the article on the stretch, with the interlinked units in close contact.

Another object is the provision of a simple and inexpensive construction, adapted to support a maximum of articles in a minimum of space.

With these and other objects in view the invention consists in the construction and novel combination of parts fully described herein-after, illustrated in the accompanying drawings and pointed out in the claims appended hereto, it being fully understood that various changes in the form, proportion, size and minor details of construction within the scope of the claims may be resorted to without departing from the spirit of the invention.

In the drawings, forming a part hereof:—

Fig. 1 is a transverse section of a plating tank provided with the improved hanger.

Fig. 2 is a section of a part of the tank taken at right angles to Fig. 1.

Fig. 3 is a side elevation of an alternate construction.

The embodiment of the invention of Figs. 1 and 2 is shown in connection with a plating tank 1, of usual construction, provided with one or more cross bars 2 for supporting the hangers, the cross bars resting at their ends on the walls of the tank, and the bars may be arranged longitudinally or transversely of the tank, as may be desired. The bars and the remaining elements to be described, are of conducting material.

The hanger includes a substantially rectangular frame composed of end members 3, a bottom member 4, and a top member 5. The ends 3 and the bottom member 4 are continuous, and the top member 5 is secured to the end members 3, and is spaced apart from the upper ends of the said members, each of which is provided with a hook 6, as shown more particularly in Fig. 2. The tank is provided with the usual anodes 7, with which the positive lead of the circuit is connected, the negative lead being connected with the cross bars 2, or directly with the hanger, as may be desired.

The improved rack is especially designed for supporting articles composed of similar interlinked units, a chain 8 being shown in the present instance. The lower bar 4 is provided with a number of hooks 9, each of which is electrically connected to the bar by welding or the like, and the upper bar 5 is provided with a series of depending coil springs 10, each being electrically connected with the said member.

Each spring has a hook 11 at its lower end, and the articles 8 are engaged at one end with the hook 9, and at the other with the hook 11. At the time of engagement the spring is expanded, and it will be apparent that when it is released, it will contract, and extend the article, causing the links to contact closely.

If desired, a spring may be arranged at each end of the article, as shown in Fig. 3. In this illustration, the frame indicated generally at 12, is similar in construction to that

shown in Fig. 1, except that the hooks 9 of Fig. 1, are replaced by spring 13 connected with the lower member, each having a hook 14 at its upper end to engage the lower end 5 of the article. The upper springs 15 are similar to the springs 10, and similarly arranged.

The springs 10 and the hooks 9 are in register, as are also the springs 13 and 15, so that the article hangs vertically. As many sets of 10 springs and hooks, or springs, may be connected with a hanger as the nature of the article and the size of the frame permits. When the current flows from the anode to the cathode, it passes on to the frame and to the negative electrode, with a good electrical connection between the interlinked units.

What is claimed as new is:—

1. In a hanger for supporting flexible articles of interlinked units, a frame of conducting material having opposite members thereof provided with means to engage the end units and to put the articles on the stretch when so engaged.

2. In a hanger for supporting flexible articles of interlinked units, a frame of conducting material having opposite members thereof provided with means to engage the end units and to put the articles on the stretch when so engaged, said last named means including springs.

3. In a hanger for supporting flexible articles of interlinked units, a substantially rectangular frame having hangers at its top and article supports, each including a pair of 35 hooks, the members in substantial register and secured to opposite members of the frame.

4. In a hanger for supporting flexible articles of interlinked units, a substantially rectangular frame having hangers at its top and 40 article supports, each including a pair of hooks, the members in substantial register and secured to opposite members of the frame, and a spring interposed between one of the hooks and the frame.

45 5. In a hanger for supporting flexible articles of interlinked units, a substantially rectangular frame having hangers at its top and article supports, each including a pair of hooks, the members in substantial register 50 and secured to opposite members of the frame, and springs interposed between the hooks and the frame.

Signed at New York city in the county of New York and State of New York this 5th 55 day of November, A. D. 1928.

LOUIS LICHTMAN.
